United States Patent Office

Des. 187,882
Patented May 10, 1960

187,882

SOCK

Robert E. Wooten, Burlington, and Otis W. Holder, Mount Airy, N.C., assignors to Patent-Hose Corporation, Burlington, N.C., a corporation of North Carolina

Application September 5, 1958, Serial No. 52,518

Term of patent 14 years

(Cl. D47—7)

Figure 1 is an elevational view of a sock showing our new design with portions of the foot thereof being shown in phantom lines; and

Figure 2 is an enlarged fragmentary view of the outer surface of that part of the sock defined by broken lines in Figure 1 and indicated by the numeral 2.

The dominant feature of our design resides in the contrasting appearance resulting from the coarsely knit cuff portion and finely knit foot portion and by forming the foot portion with substantially twice the number of wales as the cuff portion substantially as shown.

We claim:

The ornamental design for a sock, substantially as shown and described.
